R. H. WORRELL

MINE TIE

Original Filed Feb. 6, 1926

R. G. Thomas

R. H. Worrell

INVENTOR

BY Victor J. Evans

ATTORNEY

WITNESS:

UNITED STATES PATENT OFFICE.

ROBERT H. WORRELL, OF BECKLEY, WEST VIRGINIA, ASSIGNOR TO WORRELL MINE TIE MANUFACTURING COMPANY, OF BECKLEY, WEST VIRGINIA, A CORPORATION.

MINE TIE.

Application filed February 6, 1926, Serial No. 86,560. Renewed November 2, 1927.

This invention relates to ties particularly adapted for mine work, the general characteristic being the provision of channeled portions therein adapted to serve as a traction surface for the tie upon the floor of a mine tunnel.

An object of the invention embodies fastening means upon the tie adapted for selective engagement with the feet of the rails supported thereon to permit the removal of the track to other parts of a mine recently opened.

More specifically stated, the tie and fastening means provide registering depressed portions for holding the fastening means in a locked position upon the tie for retaining the rails in place thereon.

With the above and other objects in view, the invention further includes the following novel features and details of construction, to be hereinafter more fully described, illustrated in the accompanying drawings and pointed out in the appended claims.

In the drawing:—

25 Figure 1 is a fragmentary perspective of my invention carrying the portion of a rail thereon;

Figure 2 is a top plan view of the tie with the fastening means swung to an open position;

Figure 3 is a sectional view taken on the line 3—3 of Figure 1.

Referring to the drawings in detail, wherein like characters of reference denote corresponding parts, the reference character 10, indicates a tie, preferably constructed of metal, said tie having upwardly raised channeled portions 11 arranged adjacent the respective sides thereof and defining the downwardly extending channeled portion 12 therebetween in the manner as illustrated in Figure 3 of the drawing.

The opposite side edges of the tie carry outwardly extending flange portions 13 arranged in direct alignment with the lower surface and underside of the central channeled portion 12, whereby a seat and track surface is provided for the tie. Stationary plates 14 positioned adjacent the ends of the tie provide upwardly and obliquely disposed inner side edges 15 between the undersides of which and the upper side of the tie is fitted the outer side of the foot 16, of the rails 17.

Locking plates 19 provide correspondingly disposed inner end portions 18 engageable

with the opposite sides of the foot of the rail to rigidly hold the latter upon the tie. Each of the plates 19 provides transversely disposed bent portions 20, the purpose of which will be presently described. Such plates have headed studs 23 extending therethrough and pivotally mounting the same upon the upper side of the tie in order that the end portions 18 thereof may be swung to their respective positions as illustrated in Figures 1 and 2 of the drawing. The locking means for such plates consists of depressed pockets 21 which when swung with the plate over the tie as illustrated in Figure 1 of the drawing, are adapted to register and drop down and within the central channeled portion 12 thereof to sustain such plates thereon against accidental displacement and retrograde movement whereby the rails as supported, will not only be held upon the ties, but will be equi-distantly positioned thereon. The respective inner end portions of the locking plates 19 form curved portions 22 under which a crow-bar or like instrument may be inserted to permit its end portion to engage the upper side of the central channeled portion 12, and upon upward movement will raise the depressed pockets 21 therefrom whereby the locking plates may be swung to their released positions as illustrated in Figure 2 of the drawing. The bent portions 20 of the locking plates 19 normally tension the depressed pockets 21 within the central channel portion 12.

Manifestly the rails 17 may be readily disengaged when it becomes necessary to move the track to another portion of the mine opened up in order that a material saving of time is enhanced and no spikes are necessary in the securing of the rails upon the ties.

The invention is susceptible of various changes in its form, proportions and minor details in the construction and the right is herein reserved to make such changes as properly fall within the scope of the appended claims.

Having thus described my invention what is claimed is:—

1. A rail fastening comprising a tie having a longitudinal channel portion, a rigidly mounted rail engaging plate provided upon one end of the tie and a swingingly mounted rail engaging plate arranged upon the corresponding end of the tie and upon the oppo-

site side of the rail and having a channeled portion therein adapted for reception within a channeled portion of the tie whereby the swingingly mounted rail engaging plate is 5 detachably secured thereto.

2. A mine tie comprising channeled portions provided upon its upper side and intermediate portion thereof, a rigidly secured plate extending transversely adjacent one 10 end of the tie and having an upwardly and obliquely disposed inner side edge adapted to receive the adjacent side of a rail therein, a swingingly mounted rail engaging plate having a correspondingly constructed outer 15 end for engagement with the corresponding side of the rail, said plate including a bent portion at an appropriate point in its length for tensioning its inner end downwardly upon the upper side of the tie, the inner end of the swingingly mounted rail engaging plate having a depressed transversely disposed channeled portion provided therein and adapted for engagement within the corresponding central 20 channel portion of the tie, and the inner extremity of the swingingly mounted rail engaging plate terminating in a curved portion to permit the insertion of a lever thereunder in order that the depressed portion of the plate may be removed and swung to an open position in order that the rail may be readily disengaged from its moorings upon the tie.

3. A mine tie comprising channeled portions provided upon its upper side and intermediate portion thereof, a rigidly secured 30 plate extending transversely adjacent one end of the tie, said plate having an upwardly and obliquely disposed inner side edge

adapted to receive the adjacent side of a rail therein, a swingingly mounted rail engaging plate having a correspondingly constructed outer end for engagement with the corresponding side of the rail, said plate including a bent portion at an appropriate point in its length for tensioning its inner end downwardly upon the upper side of the tie, the inner end of the swingingly mounted rail engaging plate having a depressed transversely disposed channeled portion provided therein and adapted for engagement within the corresponding central 40 channel portion of the tie, and the inner extremity of the swingingly mounted rail engaging plate terminating in a curved portion to permit the insertion of a lever thereunder in order that the depressed portion of the plate may be removed and swung to an open position in order that the rail may be readily disengaged from its moorings upon the tie.

4. A rail fastening comprising a tie having a longitudinal channel on its upper face, a rail foot engaging plate pivoted eccentrically at the side of said channel, the tail of said plate arranged to enter said channel between its sides and to be held thereby in 50 locked position.

In testimony whereof I affix my signature.

ROBERT H. WORRELL.
